DISPENSER FOR FASTENERS

Filed June 20, 1929 2 Sheets-Sheet 2

UNITED STATES PATENT OFFICE

KENLY C. BUGG, OF ST. LOUIS, MISSOURI

DISPENSER FOR FASTENERS

Application filed June 20, 1929. Serial No. 372,327.

This invention relates to dispensers for fasteners and has special reference to dispensers for discharging fasteners successively and one at a time from a receptacle containing the fasteners.

An object of the invention is to provide a device for dispensing successively and individually nails, tacks, rivets, and similar fasteners so that the workman will be supplied with these fasteners just as rapidly as he can make use of them and in position most convenient to the workman.

Another object of the invention is to provide a device of the character and type mentioned comprising a magazine containing one or more chutes or guides for containing and delivering the fasteners, in combination with means in connection with one end of the device controlling delivery or discharge of the fasteners so that only one of the fasteners is released and delivered and discharged at each operation.

Another object of the invention is to provide a device of the character and type mentioned comprising a body having a series of guides or chutes therein for containing the fasteners in parallel and superimposed relationship, in combination with means for discharging the fasteners from said chutes selectively.

Other objects will appear from the following description, reference being made to the drawings in which

Fig. 1 is a front elevation of my improved dispenser for fasteners.

Fig. 2 is a side elevation of the dispenser.

Fig. 3 is a side elevation of the dispenser opposite from that shown in Fig. 2.

Fig. 4 is an upper end elevation.

Fig. 5 is a lower end elevation.

Fig. 6 is a lower end elevation of the dispenser with the control device controlling the release and discharge of the fasteners removed.

Fig. 7 is an upper end elevation of the end cap removed.

Fig. 8 is a view showing the upper side of the discharge device removed from its associated parts.

Fig. 9 is an upper side elevation of the de-

vice that is adjustable to determine from which chute or guide the fasteners may be taken.

Fig. 10 is a vertical sectional view of the lower end of the device transversely of the guide chutes and of the stems of the fasteners contained therein.

Fig. 11 is a vertical sectional view at right angles to that of Fig. 10.

My improved dispenser for headed and stemmed fasteners comprises an elongated body 1 having in one side thereof a wide groove 2 (Fig. 7) into which open a number of parallel grooves or slots 3. The under side of the groove 2 is covered by a plate 4 having its vertical side edges 5 bent so as to seat against the side of the body 1. A number of removable screws 6 pass through the edges 5 of the plate 4 and into the side portions of the body 1, thereby removably securing said plate in the position shown.

The grooves or slots 3 constitute guide chutes to receive the stems of headed and stemmed fasteners 7 (Figs. 10 and 11). These guide chutes 3 will not receive the heads of the fasteners 7 but the heads of said fasteners are in the groove 2 outside of the guide chutes 3. Thus, the stems of the fasteners 7 extend transversely of the body 1 and in approximately parallel relationship with each other, while the heads of the fasteners are overlapped by the stems of the fasteners next above and below, as will be understood by reference to Fig. 11. This makes it impossible for the stems of the fasteners to assume vertical positions because the depth of the groove 2 is less than the width or diameter of the heads of the fasteners. Accordingly, the stems of the fasteners must remain extended into the guide chutes 3 while the heads of the fasteners must remain in the groove 2. The guide chutes 3 may be easily loaded with the fasteners either manually or otherwise through the open upper ends of said guide chutes.

The device is provided with a removable cap plate 8 having downturned side edges 9 engaging opposite sides of the body 1. Said plate 8 is formed with a key-hole slot 10 receiving the head of a screw 11 so as to

hold the plate 8 releasably clamped upon the end of the body 1 in an obvious manner, as shown in Fig. 4. One side edge of the plate 8 is formed with a handle 12 for convenience in removing and applying the plate 8. The body has removably attached to its rear side a hook or bracket 13 for engagement with any appropriate support. This hook or bracket is held in connection with the body 1 by removable screws 14.

A base 15 is connected with the lower end of the body 1. This base has dove-tail sliding connection 16 with the body 1 so that said base may be moved to different adjusted positions transversely of the lower ends of the guide chutes 3. The dove-tail connection supports the base 15 in connection with the body 1 and permits adjustment of the base on the body. A bracket 17 is removably attached to one side of the body 1 by removable screws 18. A plunger 19 is mounted for vertical sliding movements in the bracket 17 and has a pointed lower extremity 20 designed and arranged to be engaged selectively in recesses 21, 22, 23 and 24 in a laterally projecting portion of the base 15. These recesses are coordinated with respect to the guide chutes 3 so that when the point 20 is engaged in the recess 21 a chute 25 through the base 15 is in registration with and continuation of the chute 3 that is toward the extreme right as seen in Fig. 10; when the point 20 engages in the recess 22 the chute 25 is in registration with and in continuation of the chute 3 that is second from the extreme right as shown in Fig. 10; when the point 20 is seated in the recess 23 the chute 25 is in registration with and in continuation of the guide chute 3 next to the left from the guide chute with which the chute 25 is shown in registration in Fig. 10; and when the point 20 is seated in the recess 24 the chute 25 is in registration with and in continuation of the chute 3 at the extreme left of Fig. 10. A coil spring 26 encircles the stem of the plunger 19 below the bracket 17 and has its lower end pressing against the head of the point 20 and its upper end pressing against the bracket 17. This spring 26 is effective to hold the point 20 firmly engaged in any of the recesses 21, 22, 23 and 24. The upper end of the plunger 19 is equipped with a handle 27 for manual engagement to withdraw the plunger from engagement with the base 15 so as to permit said base to be moved from one adjustment to another. When the handle 27 is released the spring 26 acts to seat the head 20 in the proper recess so as to hold the base 15 properly adjusted.

The chute 25 has at its outer end a widened enlargement 28 which is of sufficient width to receive the heads of the fasteners while the stems of the fasteners are received in the chute 25. The walls 29 of the widened slot portion 28 are in continuation of the bottom

wall of the groove 2 so that the heads of the fasteners may pass smoothly into the widened slot portion 28. A block 30 is secured in a recess in the lower side of the base 15 by a removable screw 31 and has its inner end in continuation of the adjacent wall of the chute 25 and the upper portion of its outer edge adjacent to its inner end in continuation of one of the walls 29. The lower corner of the block 30 is cut away or removed to provide a notch 32. An arm 33 projects from the opposite side of the chute 25 and has in its lower corner a notch 34 opposite the notch 32. These notches are to receive the heads of the fasteners where the fasteners pass thereto from a relationship in which the head of the lower fastener is against the inner side of the head of the upper fastener; or where said fastener passes thereto from a relationship in which the head of the lower fastener is on the outside of the head of the next upper fastener. That is to say, the notches 32 and 34 provide room to receive the heads of the fasteners irrespective of the overlapping relationship in which the fasteners are discharged.

The under side of the base 15 has therein a spring seat 35 in which is mounted a coiled spring 36. A plate 37 is attached by means of removable screws 38 to flanges 39 projecting downwardly from the side edges of the base 15. This plate 37 has projecting downwardly therefrom a jaw 40 the inner side of which is approximately in the plane of one of the walls of the chute 25. A flange 41 extends along one vertical edge of the jaw 40 approximately in continuation of the wall of the widened chute portion 28 opposite from the walls 29 so as to form an abutment or guide for the outer sides of the heads of the fasteners when the fasteners are discharged. The outer side of this jaw 40 has a groove 42 designed and adapted to receive the end of the finger or hand of the user. The bottom wall of this groove intersects the opposite wall of the jaw 40 above the lower end of said jaw so that when one of the fasteners drop downwardly toward the lower end of the jaw 40 the stem of the fastener extends across the plane of the opening from the groove 42 to the opposite side of the jaw 40. This permits the finger or thumb of the workman to engage the stem of the fastener.

A slide 43 is mounted between the plate 30 and the lower edge of the base 15 and has a projection 44 extending into the spring seat 35 opposite one end of the spring 36. Thus, the spring 36 is effective to hold the plate 43 in position in which said plate extends across and closes the lower end of the chute 25 and supports the fasteners 7. A shoulder 45 on the end of the slide 43 limits the extent of movement of said slide by said spring 36. A jaw 46 is rigid with the slide 43 and extends opposite the jaw 40 and has in its outer side

a groove 47 intersecting the inner wall of said jaw 46 above the lower end thereof. Thus, when a fastener drops down between the jaws 40 and 46 it extends across the 5 notches at the lower ends of the grooves 42 and 47 and may be grasped conveniently by the fore finger and thumb of the workman.

A block 48 is attached to the upper side of the slide 43 and constitutes an abutment to limit extent of movement of said slide in a

direction in which the paw 46 is moved toward the jaw 40. The abutment 48 contacts with the adjacent end of the base 15 and thereby prevents further movement of said slide.

15 A spring finger 49 is attached to the upper side of the block 48 by a removable screw 50. This spring finger projects into a groove 51 in the lower side of the base 15. This groove 51 intersects the chute 25 so that when the 20 slide 43 is moved in opposition to the spring 36 the spring finger 49 will be projected between the stems of the lower two fasteners 7. Thus, when the slide 43 is moved inwardly in opposition to the spring 36 the finger 49

25 passes above the stem of the lowest fastener 7 and below the stem of the next adjacent fastener and thereby separates the two lowest fasteners from each other and permits the lowest fastener to drop between the jaws 40 and 46 while said finger 49 supports the remainder of the fasteners and prevents their discharge. When the pressure on the slide 43 is removed the spring 36 returns said slide to its initial or starting position, removing the finger 49 from below the fasteners 7 and passing the slide 43 below the fasteners (Fig. 10).

It is now clear that when the device is to be used the base 15 is adjusted to a position in which the chute 25 is in registration with and in continuation of the desired chute 3. The base 15 supports the fasteners 7 in the various chutes 3 which do not register with the chute 25. The chute 25 is kept filled with the fasteners from the chute 3 with which said chute 25 registers. The fasteners may be removed one at a time by operating the slide 43 first in opposition to the spring 36 to separate and discharge one of the fasteners, and then permitting the spring 36 to restore the chute to its initial or starting position. The device may be operated very rapidly and dispenses with the need and present practice of workmen carrying a quantity of fasteners in a pocket or receptacle and serving them successively from their lips.

The construction, arrangement and relationship of the parts and the number and capacity of the chutes may be varied as desired without departure from the nature and principle of the invention. I do not restrict myself in these or other unessential particulars, but what I claim and desire to secure by Letters Patent is:—

1. A dispenser for fasteners comprising a

chute arranged to contain the fasteners, a rigid jaw beyond one end of the chute, a slide between said jaw and said chute, means for holding said slide in position to support the fasteners in the chute and permitting movement of said slide to position to discharge a fastener from the chute, and a jaw on said slide cooperating with said rigid jaw to form a guide for the fasteners discharged from the chute. 75

2. A dispenser for fasteners comprising a chute arranged to contain the fasteners, a rigid jaw beyond one end of the chute, a slide between said jaw and said chute, means for holding said slide in position to support the fasteners in the chute and permitting movement of said slide to position to discharge a fastener from the chute, a jaw on said slide cooperating with said rigid jaw to form a guide for the fasteners discharged from the chute, and means in connection with said slide preventing discharge of more than one fastener from said chute at a time. 85

3. A dispenser for elongated fasteners comprising a chute for containing the fasteners, a slide at one end of the chute for supporting the fasteners in the chute, means holding said slide in position to support the fasteners in said chute and permitting movement of said slide to position to discharge a fastener from the chute at each movement of said slide, a device for operating said slide and for guiding the fasteners discharged thereby, and means in connection with said slide preventing discharge of more than one fastener at a time. 90

4. A dispenser for elongated fasteners comprising a chute for containing the fasteners, a slide at one end of the chute for supporting the fasteners in the chute, means holding said slide in position to support the fasteners in said chute and permitting movement of said slide to position to discharge a fastener from the chute at each movement of said slide, means in connection with said slide preventing discharge of more than one fastener at a time, a rigid jaw beyond the chute, and a jaw in connection with said slide cooperating with said rigid jaw to guide the fasteners that are discharged from the chute as aforesaid. 105

5. A device of the character described comprising a body having therein a chute for the stems of fasteners having stems and heads and said body having a groove beyond said chute for containing the heads of the fasteners, mechanism for discharging the fasteners from said chute and said groove individually and one at a time, and a device for operating said mechanism and for guiding the fasteners discharged thereby. 110

6. A device of the character described comprising a body having therein a chute for the stems of fasteners having stems and heads and said body having a groove beyond said

chute for containing the heads of the fasteners, mechanism for discharging the fasteners from said chute and said groove individually and one at a time and preventing discharge of more than one fastener at a time, a rigid guide member, and means operating said mechanism and cooperating with said guide member to guide the fasteners that are discharged from said chute as aforesaid.

10. A dispenser for fasteners of the stem and head type comprising a body having a number of chutes to contain the stems of the fasteners and a groove to contain the heads of the fasteners, a rigid jaw beyond one end 15 of the chutes and grooves, a slide between said jaw and said chutes and grooves having as opening therethrough for the discharge of fasteners from said chutes and groove, a jaw on said slide cooperating with said rigid jaw 20 to guide the fasteners discharged from said opening in said slide, and means for holding said slide in position to support the fasteners in said chutes and groove and permitting movement of said slide to position to permit 25 a fastener to pass through said opening in said slide.

8. A dispenser for fasteners of the stem and head type comprising a body having a chute to contain the stems of the fasteners 20 and a groove to contain the heads of the fasteners, a rigid jaw beyond one end of the chute and groove, a slide between said jaw and said chute and groove having an opening therethrough for the discharge of fasteners 25 from said chute and groove, means for holding said slide in position to support the fasteners in said chute and groove and permitting movement of said slide to position to permit a fastener to pass through said opening 30 in said slide, a jaw on said slide cooperating with said rigid jaw to guide the fasteners discharged from said opening in said slide, and an element in connection with said slide and operated thereby to prevent discharge of more than one fastener at a time 35 from said chute.

9. A dispenser for fasteners of the stem and head type comprising a body having a chute to contain the stems of the fasteners 40 and a groove to contain the heads of the fasteners, a rigid jaw beyond one end of the chute and groove, a slide between said jaw and said chute and groove having an opening therethrough for the discharge of fasteners 45 from said chute and groove, means for holding said slide in position to support the fasteners in said chute and groove and permitting movement of said slide to position to permit a fastener to pass through said 50 opening in said slide, an element in connection with said slide and operated thereby to prevent discharge of more than one fastener at a time from said chute, and means supported by said slide and cooperating with 55 said jaw to form a guide for the fasteners

discharged through said opening in said slide.

10. A dispenser for fasteners of the stem and head type comprising means forming a chute arranged to contain the stems of the fasteners and a groove arranged to contain the heads of the fasteners, a rigid jaw beyond one end of the chute and groove, a slide between said jaw and said chute and groove having an opening therethrough for the passage of fasteners from said chute and groove, means holding said slide in position to support the fasteners in said chute and groove and permitting movement of said slide successively to a position to discharge fasteners 70 successively from said chute and groove, and a jaw on said slide cooperating with said rigid jaw to form a guide for the fasteners discharged from said chute and groove. 75

11. A dispenser for fasteners of the stem and head type comprising means forming a chute arranged to contain the stems of the fasteners and a groove arranged to contain the heads of the fasteners, a rigid jaw beyond one end of the chute and groove, a slide between said jaw and said chute and groove having an opening therethrough for the passage of fasteners from said chute and groove, means holding said slide in position to support the fasteners in said chute and groove and permitting movement of said slide successively to a position to discharge fasteners 80 successively from said chute and groove, a jaw on said slide cooperating with said rigid jaw to form a guide for the fasteners discharged from said chute and groove. 85

12. A dispenser for fasteners of the stem and head type comprising means forming a chute arranged to contain the stems of the fasteners and a groove arranged to contain the heads of the fasteners, a rigid jaw beyond one end of the chute and groove, a slide between said jaw and said chute and groove having an opening therethrough for the passage of fasteners from said chute and groove, means holding said slide in position to support the fasteners in said chute and groove and permitting movement of said slide successively to a position to discharge fasteners 90 successively from said chute and groove, a jaw on said slide cooperating with said rigid jaw to form a guide for the fasteners discharged from said chute and groove. 95
